(57) **CLAIM**

The ornamental design for a hose removal tool, as shown and described.

DESCRIPTION

FIG. 1 is a perspective view of the hose removal tool; FIG. 2 is a top view of the hose removal tool; FIG. 3 is a bottom view of the hose removal tool; FIG. 4 is a first side view of the hose removal tool; FIG. 5 is a second side view of the hose removal tool; FIG. 6 is a front view of the hose removal tool; and, FIG. 7 is a rear view of the hose removal tool. All broken lines illustrate portions of the hose removal tool that form no part of the claimed design.
